UNITED STATES PATENT OFFICE

1,945,464

GAS PRODUCER

Jesse D. Thomas, St. Petersburg, Fla.

Application April 11, 1933. Serial No. 665,597

3 Claims. (Cl. 261—77)

This invention relates to gas producers of the air and liquid contact type and it proposes the provision of a carburetting device for making gas from any commercial grade of gasoline, for heating, lighting and general household purposes.

One of the objects of the invention is the provision of means for maintaining a recurrent circulation of gasoline from a reservoir through a mixing chamber, and the bringing of air by a circuitous route into successive contacts with successive surface portions of the circulating gasoline within said mixing chamber, for carburetting said air.

Another object of the invention is to provide a venturi as the liquid fuel circulation means, at the bottom of a column of the circulating liquid, and fed with air under pressure, entraining air in said column and increasing the flow velocity of the gasoline through said column to the extent that the liquid particles separate, permitting expansion of the air in said column and increasing its surface presentation to the liquid fuel.

A further object of the invention is to provide for the avoidance of stagnant fuel bodies in the mixing chamber which, once deprived of their volatile fractions, might thereafter remain inert as to their carburetting function, reducing the capacity of the machine.

Still another object of the invention is to provide baffles, preferably wick-lined dipping into the surface of the circulating gasoline within said mixing chamber, and determining the labyrinthine course of the air being carburetted, said baffles being so arranged that passage is maintained for the flow of liquid fuel along the bottom of said mixing chamber from the inlet to the discharge end thereof.

Other objects of the invention will appear as the following description of a preferred and practical embodiment thereof proceeds.

In the drawing which accompanies and forms a part of the following specification and throughout the several figures of which the same characters of reference have been employed to designate identical parts,

Figure 1 is a view in elevation illustrating a system in which the carburetting device of my invention is intercalated;

Figure 2 is a vertical section through a carburetting device; and

Figure 3 is a section taken along the line 3—3 of Figure 2.

Referring now in detail to the several figures, 55 a supply of air under pressure is maintained in

the tank 1 by means of a compressor 2 run by a motor 3. A pressure actuated switch 4, diagrammatically shown and forming no part of the present invention interrupts the motor circuit when the desired pressure has been attained in 60 the tank 1.

The air under pressure is led by way of a conduit 5 to the carburetting unit which in general is designated by the reference character 6. The air serves as the medium to be carburetted as 65 well as the motive power by means of which the functions of the carburetting unit are carried out.

The carburetting unit 6 comprises in its preferred form, a two storied tank constituting the 70 lower reservoir 7 which may be filled with raw gasoline through the fitting 8. The upper part of the unit 6 comprises a mixing chamber 9 having the bottom wall 10, the same functioning as a partition between the two parts of the carburetting 75 unit. The bottom 10 is preferably level. It is provided with an overflow into the tank 7 by way of a nipple 11 up-standing for about an inch above the bottom wall 10 so as to impound a shallow body of gasoline in the mixing chamber 80 which is constantly changing, being part of the liquid circulation system about to be described.

A stand pipe 10 affords communication between the bottom of the reservoir by means of the venturi fitting 12, and with the upper part 85 of the mixing chamber by means of the spout 13 which is located at the opposite end of the mixing chamber from the overflow nipple 11. Compressed air from the tank 1 is supplied to the venturi 14 by a branch pipe 24 and issues 90 from the nozzle 14 of the venturi in the form of a jet which aerates the column of liquid in the stand pipe, throwing a jet of commingled air and gasoline from the spout 13 into the mixing chamber. The liquid constituent of this 95 aerated column falls to the shallow body of gasoline in the bottom of the mixing chamber and causes its overflow through the nipple 11 back to the reservoir 7. Thus circulation of gasoline is maintained and a fresh body of gasoline 100 is perpetuated in the mixing chamber.

The mixing chamber is provided between the inlet and the discharge ends with a series of baffles 15 and 16' arranged in alternate relation, the baffles 15 depending from the top wall 16 105 of the mixing chamber while the baffles 16' are spaced from said top wall as well as from the bottom of the mixing chamber, being supported by angles 17 from the side walls 18 and 19 of the mixing chamber, best shown in Figure 3. 110

The lower ends of the baffles 16' dip below the level of the body of gasoline in the mixing chamber which level is determined by the height of the nipple 11. The baffles 15 terminate at their lower ends a slight distance above this level. Air is admitted to the space anterior to the first of the baffles 15 through a valve controlled branch of the air supply pipe 5.

In operation, the high velocity imparted to the liquid fuel in the stand pipe 10 causes the particles of liquid to separate, permitting the air bubbles which are fairly condensed at their moment of emergence from the nozzle of the venturi, to expand progressively as they approach the top of the stand pipe, presenting ever increasing surfaces to the liquid in the aerated column, thus enhancing the absorption by the air of the volatile gasoline. The mixture of gasoline and air issuing from the spout 13 into the space anterior to the first baffle 15, impinges against a sheet of wicking 19 with which said baffle is furnished on its forward face, wetting said wicking and enhancing the evaporative efficiency of this portion of the mixing chamber. The heavier liquid constituents issuing from said spout drop into the shallow body of gasoline in the bottom of the mixing chamber agitating it and thoroughly mixing the fresh gasoline with that already in the mixing chamber, also inducing a flow of the lower stratum of gasoline beneath the baffles 17 and in the direction of the overflow 11, bringing fresh gasoline into the space between each of the baffles 16' and thus renewing the volatility of each portion of gasoline in the mixing chamber, segregated in their surface portions by the baffles 16'.

The baffles 16' which dip into the liquid fuel are also furnished on their forward sides with sheet wicking 19 which is continually wetted by capillarity. Air from the branch pipe 5' entering the space between the first baffle 15 and the adjacent wall of the mixing chamber, dilutes the carburetted air issuing from the spout 13 and evaporating from the wick 19, said air flowing in serpentine manner alternately beneath the baffles 15 and above the baffles 16', being forced into a thin film beneath each of the baffles 15, in which thin condition it makes contact with the surface of the body of gasoline in the mixing chamber absorbing volatile fractions of gasoline from said body of gasoline.

After having been thus passed into proximity to the body of gasoline in the mixing chamber a plurality of times and having flowed adjacent the gasoline-wet wicking on each of the baffles 16', the air when it reaches the ultimate space between the final baffle 15 and the adjacent wall of the mixing chamber, is thoroughly carburetted and ready to be burned. It is led off by a suitable eduction pipe 20 to the appliance in which the combustible mixture is burned. Adjustment in the richness of the mixture and in the rate of its carburetion may be accomplished by manipulation of either or both of the valves 25 or 26.

Figure 1 shows a valve 21 controlling the supply of compressed air to the carburetted unit, said valve being actuated by a diaphragm 22 which under the normal air pressure when gas is being discharged through the eduction pipe 20 maintains the valve 21 open, but when the valve on the gas-utilizing appliance is cut off so that the out-flow through the eduction pipe ceases, pressure in the diaphragm chamber 23 builds up, pressing the diaphragm up to the broken line

position and closing the valve, thus cutting off the supply of compressed air and producing cessation in the functioning within the carburetted unit.

While I have in the above description disclosed what I believe to be a preferred and practical embodiment of the invention, it is to be understood that the specific details of construction as illustrated and described are merely by way of example and not to be construed as limiting the scope of the invention as claimed.

What I claim is:

1. Gas producer comprising a carburetted device including a tank having an intermediate substantially horizontal partition, dividing said tank into a carburetted chamber above said partition and a reservoir for liquid fuel below said partition, an overflow pipe affording communication between said carburetted chamber and said reservoir and determining a shallow liquid fuel level above said partition in said carburetted chamber, a stand pipe affording means of communication between said reservoir below the level of liquid fuel therein and said carburetted chamber above the level of liquid fuel therein, an injector in the lower part of said stand pipe adapted to be supplied with air under pressure for discharging an aerated column of liquid fuel into said carburetted chamber thus establishing a liquid fuel circulation through the lower part of said carburetted chamber and said reservoir, a plurality of baffles in said carburetted chamber, alternating baffles extending from the roof of said chamber to a slight distance above the liquid fuel level in said chamber, and the other set of alternate baffles being spaced from the roof of said chamber and dipping beneath the liquid level therein to within a short distance of said partition, an outlet for carburetted mixture at the opposite end of said carburetted chamber, said baffles determining a sinuous course for the passage of air through said carburetted chamber, constricting it to a relatively thin film where it passes beneath alternate baffles into surface contact with the liquid fuel, the spaced relation of said baffles from said partition permitting a subsurface movement of the liquid fuel in said carburetted chamber toward said overflow, avoiding pocketing between said baffles of less volatile constituents of said liquid fuel resulting from the absorption of its volatile constituents by the current of air passing along its surface.

2. Gas producer as claimed in claim 1, the baffle first adjacent the discharge from said stand pipe having a wick surface facing said stand pipe, means for admitting air under pressure to the space anterior to the first baffle, a valve controlling said air admitting means, and a discharge for carburetted gas at a point remote from said air admitting means.

3. Gas producer as claimed in claim 1, the baffles which dip in the liquid in said carburetted chamber having wick surfaces on their anterior faces, maintained wet by capillarity, and that baffle first adjacent the discharge from said stand pipe having a wick surface facing said stand pipe and impinged by the liquid discharged from said stand pipe, means for admitting air under pressure to the space anterior to said first baffle, a valve controlling said means, and a discharge for carburetted gas at a point remote from said air admitting means.

JESSE D. THOMAS.
